ASH TRAY

Frederick W. Grantham, Winnetka, Ill., assignor
of one-half to A. S. Holway, Wilmette, Ill.

Application September 19, 1938, Serial No. 230,525

11 Claims. (Cl. 131—240)

The invention relates to improvements in ash receptacles adapted for smokers' use and has for its primary object the provision of an improved ash receptacle so constructed and arranged as to discharge a cigarette or the like placed thereon to prevent the falling of said cigarette therefrom due to continued burning, which is of simple construction and highly efficient in use.

Another object of the invention is the provision of an improved arrangement of the character indicated so constructed and arranged as to insure positive operation thereof under various conditions of use.

Other objects will appear hereinafter.

The invention consists in the combinations and arrangements of parts hereinafter described and claimed.

The invention will be best understood by reference to the accompanying drawings forming a part of this specification and in which

Fig. 1 is a top plan view of an ash tray embodying the invention;

Fig. 2 a vertical transverse section of the same taken substantially on line 2—2 of Fig. 1;

Fig. 3 a section taken substantially on line 3—3 of Fig. 2;

Fig. 4 a vertical longitudinal section of a modified form of construction;

Fig. 5 a horizontal section of the construction shown in Fig. 4;

Fig. 6 a view similar to Fig. 5 but showing another modified form of construction;

Fig. 7 a side view, shown partially in section, of another modified form of construction;

Fig. 8 a partial top plan view of the construction shown in Fig. 7; and

Fig. 9 a detailed section showing still another modified form of construction.

The embodiment of the construction illustrated in Figs. 1, 2, and 3 comprises a receptacle 10 having a raised bottom 11 arranged to support burning cigarettes or cigars discharged into said receptacle in such a manner as to prevent damage from the heat to an underlying supporting surface such as highly finished table tops. The receptacle 10 is provided with a removable cover member 11 having inwardly tapering conical mouth 13 providing a central entry opening 14 through which ashes, cigarettes and cigar stubs may be inserted into the receptacle 10.

Brackets 15 are secured as shown at diametrically opposite points of the under side of the mouth 13 and provided with depending perforated supporting ears 16 and pivotally supporting two trap doors 17 on pivot pins 18 sup-

ported by the ears 16 as shown. Each trap door 17 is provided with an outwardly extending operating arm 19 to facilitate manipulations thereof. Supporting brackets 20 are secured as shown to diametrically opposite points of the top side of the mouth 13 directly above the brackets 15 and are provided as shown with upwardly and inwardly extending perforated supporting ears 21. Pivotaly mounted on each of the brackets 20 is a cigarette or cigar support 22 having depending perforated ears 23 pivotally supported on a supporting pin extending between the ears 21 as shown. A thermostatic element 24 in the form of a curved leaf is arranged as shown in an opening in the bottom of each support 22, where it will be subjected to the heating action of a lighted cigarette or cigar stub placed upon the corresponding support 22, as indicated by the dotted lines in Fig. 2. The free end of each thermostatic member 24 is provided with an electric contact 25 cooperating with another electric contact 26 mounted on the mouth 13 of the cover 12 in cooperative relation therewith. Each contact 26 is connected by a wire 27 with a solenoid 28, said solenoid being connected by wires 29 and 29' with one end of an electric battery 30 mounted in suitable clips as shown in the lower portion of the receptacle 10, the other end of said battery being grounded on said receptacle, thereby placing each of the supports 22 in electrical connection with said battery.

The core 31 of each of the solenoids 28 is connected as shown with the operating arm 19 of the corresponding trap door 17.

When a lighted cigarette or cigar is laid upon one of the supports 22 and continues to burn, as soon as the heat thereof reaches the thermostatic leaf 24, said leaf operates automatically to cause the contact 25 to touch the contact 26 thereby closing the electric circuit through the solenoid 28. Excitation of the solenoid 28 raises the corresponding core 31, thereby operating the corresponding trap door 17 to depress or open the same for the reception of the cigarette stub from the support 22. Each trap door 17 is connected by a suitable link 17' with the corresponding support 22 so that depression of the same automatically and simultaneously tilts said support upwardly as indicated by the dotted lines at the right of Fig. 2 to discharge positively the object resting thereon. Upon discharge of the burning object, the heat thereof is removed from the thermostatic element 24, thereby breaking the circuit through the solenoid 28 and releasing the parts for return to normal positions under

the influence of the weights thereof, the support 22 being so pivoted as to automatically return of its own weight and the weight of the corresponding core 31 serving as sufficient weight to 6 return the corresponding trap door 17.

In this way, when a lighted cigarette or cigar stub is laid upon one of the supports 32, and forgotten by the smoker, its continued burning will cause its automatic, positive, and complete 10 discharge into the ash tray, and will thereby prevent its toppling outwardly onto the supporting surface of the ash tray when its consumption has continued long enough to cause the protruding outer end to outweigh the consumed inner 15 end thereof.

Thus the highly polished surface of table tops upon which the ash trays may rest will be automatically and perfectly protected from accidental burning and marring by cigarette or cigar 20 stubs toppling from the supports onto said table tops.

In the modified form of construction illustrated in Figs. 4 and 5, the ash receptacle 32 is made roughly in the form of the body of a pelican. The part 33 representing the lower bill of the pelican is pivotally mounted at 34 to swing upwardly and inwardly to imitate the gulping or eating action of a pelican. A support for a cigarette or cigar stub is arranged at the outer 30 end of the part 33 in the form of a bent leaf spring 35 of thermostatic material which carries an electric contact 36 cooperating with a corresponding contact 37 on the part 33 and connected by wire 38 with the solenoid 28 which in 35 turn is connected by wire 39 with the battery 30 positioned as shown in the upper rear portion of the body 32. The core 31 of the solenoid 28 is connected by a link 31' with one side of the part 33 so that excitation of the solenoid 28 will 40 cause depression of the inner end of the part 33, thereby raising its outer end to cause a supported cigarette or cigar stub to be discharged into the body 32. In this way substantially the same results as before are obtained and at the 45 same time the impression given that the represented pelican is actually swallowing or gulping the cigarette or cigar stub, thereby furnishing an attractive table or desk ornament.

In the modification illustrated in Fig. 6, a 50 lever 40 is pivotally mounted at 34 in the bill part 33 of the pelican figure and is provided at its outer end with a support 40' for a cigarette or cigar stub. An electric contact 41 is arranged as shown on the under side of the support 40' to 55 cooperate with a stationary contact 42. The lever 40 is provided at its inner end with a weight 43 sufficient to hold the same in contact with a stop pin 44 and thereby normally hold the contacts 41 and 42 separated. However, the parts 60 are so nearly balanced that the weight of a cigarette or cigar stub on the support 40' will overbalance the weight 43 and thereby cause depression of the electric contact 41 into actual contact with a contact 42. Contact 42 is connected by 65 wire 45 with the heating coil 46 of a thermostatic switch member 47 and a wire 48 connects the other end of said heating coil with the battery 30. Thermostatic switch 47 carries a contact 49 connected by branch wire 50 with the wire 45 70 and cooperating with a contact 51 connected by wire 52 with the solenoid 28. The arrangement is such that when the contact 41 is depressed to close the circuit through the heating coil 46, the circuit through the solenoid 28 will not at once 75 be closed as contacts 49 and 51 are normally held

separated as shown in Fig. 6. However, as current flows through the heating coil 46, the thermostatic switch 47 is heated in the usual way to cause closing of the contacts 49 and 51, thereby establishing a circuit through the solenoid 28 10 after a predetermined lapse of time. Obviously, by adjusting the distance between the contacts 49 and 51 this lapse of time can be regulated as desired. As soon as the circuit is closed through the solenoid, the core thereof is drawn downwardly, thereby swinging the lower bill part 33 upwardly to cause discharge of the cigarette or cigar stub. As soon as the stub is thus discharged the weight of the parts will cause operation of contacts 41 and 42, thereby breaking the circuit 15 through solenoid 28 and releasing the parts for return to normal position due to their own weight.

In the modification illustrated in Figs. 7 and 8, two supports 53 are pivotally mounted at 54 on 20 opposite sides of the cover 12 of the ash tray 10 and are equipped with weights 55 normally holding said supports slightly tilted upwardly and outwardly as indicated. Each support carries on its under side an electric contact 56 cooperating 25 with a corresponding contact 57 connected by wire 58 with a corresponding solenoid 28'. Each solenoid 28' operates a corresponding core 31'' carrying a piston 60 loosely operating in a corresponding cylinder 61. Each piston 60 is loose 30 enough in its cylinder 61 so that there will be some leakage of air around its edges. Thus when each solenoid 28' is excited it cannot at once raise its core 31'' because of the resistance of the piston 60, but as the air gradually leaks past said 35 piston, said core will slowly rise under the influence of the magnetic action of the corresponding solenoid 28'. Each core 31'' carries a switch bar 62 cooperating with electric contacts 63 and 64. Contact 63 is connected by a branch wire with 40 the wire 58 and contact 64 is connected by wire 65 with the solenoid 28, which in turn is connected by another wire 66 with the battery 30. By this arrangement, as soon as switch bar 62 joins contacts 63 and 64, the corresponding 45 solenoid 28 will be excited to move its core 31 in the usual way. Each of the cores 31 carries a pusher arm 67 at its upper end with a push contact 68 adapted and arranged to contact with the end of a cigarette or cigar stub on the corresponding support 53, and whereby the stub resting upon the support 53 will be positively pushed therefrom and discharged into the ash tray 10.

In the modification illustrated in Fig. 9, a cigarette or cigar support 69 is pivoted at 70 and normally held in a slightly upwardly and outwardly tilted position by the action of spring 71. On its under side the support 69 carries an electric contact 72 cooperating with a contact 73 55 connected with the wire 58. A cooperating supporting bar 74 is arranged as shown adjacent the inner end of the support 69, so that a cigarette or cigar stub, laid upon the bar 74 will have its outer end resting upon the inner end of the 60 support 69, as indicated in dotted lines in Fig. 9. However, as shown, the stub thus resting on the bar 74 will be nearly balanced thereon so that the weight resting on the inner end of the support 69 will be very slight. As the inner end of the 65 stub is consumed by continued burning, the outer end thereof becomes relatively heavier and more unbalanced until its weight is sufficient to depress the support 69 to close contacts 72 and 73, thereby closing the circuit through the cor- 70 75

responding solenoid 28' with the same results as indicated above. In this way a device is provided which will be actuated by the shifting of weight or balance due to the continued burning 5 of a cigarette or cigar stub laid upon the support 69.

The specific forms and arrangements of parts disclosed are simple and effective ones for the purpose.

10 While I have illustrated and described the preferred forms of construction for carrying the invention into effect, these are capable of variation and modification without departing from the spirit of the invention. I therefore do not wish 15 to be limited to the precise details disclosed, but desire to avail myself of such variations and modifications as fall within the scope of the appended claims.

I claim:

20 1. The combination with an ash receptacle, of a support mounted thereon and arranged to discharge thereinto; an electric circuit; means operable by said circuit for discharging an object on said support into said receptacle; and means 25 operable by an object on said support for actuating said circuit.

2. The combination with an ash receptacle, of a support mounted thereon and arranged to discharge thereinto; an electric circuit; means 30 operable by said circuit for discharging an object on said support into said receptacle; and thermostatic means operable by the heat of a burning object on said support for actuating said circuit.

3. The combination with an ash receptacle, of 35 a support mounted thereon and arranged to discharge thereinto; an electric circuit; means operable by said circuit for discharging an object on said support into said receptacle; and means operable by the weight of an object on said support for actuating said circuit.

40 4. The combination with an ash receptacle, of a support mounted thereon and arranged to discharge thereinto; an electric circuit; means operable by said circuit for pushing an object from said support into said receptacle; and means operable by an object on said support for actuating said circuit.

45 5. The combination with an ash receptacle, of a support mounted thereon and arranged to discharge thereinto; a main electric circuit and a branch circuit leading therefrom; means in said main circuit automatically operating after the lapse of a predetermined time after the deposit of an object on said support to close said branch circuit; means in said branch circuit for discharging an object on said support into said receptacle; and means operable by an object on said support for actuating said main circuit.

6. The combination with an ash receptacle, of a support mounted thereon and arranged to discharge thereinto; a main electric circuit and a branch circuit leading therefrom; means in said main circuit automatically operating after the lapse of a predetermined time after the deposit of an object on said support to close said branch circuit; means in said branch circuit for discharging an object on said support into said receptacle; and means operable by the weight of 10 an object on said support for actuating said main circuit.

7. The combination with an ash receptacle, of a support mounted thereon and arranged to discharge thereinto; a main electric circuit and a 15 branch circuit leading therefrom; means in said main circuit automatically operating after the lapse of a predetermined time after the deposit of an object on said support to close said branch circuit; means in said branch circuit for discharging an object on said support into said receptacle; and means operable by the shifting of weight due to the burning of an object on said support for actuating said main circuit.

20 8. The combination with an ash receptacle, of a support mounted thereon and arranged to discharge thereinto; a trap door giving access to said receptacle; an electric circuit; means operable by said circuit for opening said trap door and discharging an object on said support into 25 said receptacle; and means operable by an object on said support for actuating said circuit.

30 9. The combination with an ash receptacle, of a support mounted thereon and arranged to discharge thereinto; a trap door giving access to 35 said receptacle; an electric circuit; means operable by said circuit for opening said trap door and discharging an object on said support into said receptacle; and thermostatic means operable by the heat of a burning object on said support 40 for actuating said circuit.

10. The combination of an ash receptacle; an electric circuit; a support pivotally mounted on said receptacle and constituting a normally open yielding switch for said circuit arranged to be 45 closed by the weight of an object thereon; and means operable by closing said circuit for discharging an object on said support into said receptacle.

11. The combination of an ash receptacle; an 50 electric circuit; a support pivotally mounted on said receptacle and constituting a normally open yielding switch for said circuit arranged to be closed by the shifting of weight due to the burning of an object thereon; and means operable by 55 closing said circuit for discharging an object on said support into said receptacle.

FREDERICK W. GRANTHAM.
